INFANT'S FEEDING SPOON OR SIMILAR ARTICLE

Estelle Kalter, New York, N.Y.
(300 Lenox Road, Brooklyn, N.Y.)

Filed Jan. 5, 1961, Ser. No. 63,454

Term of patent 14 years

(Cl. D54—12)

FIGURE 1 is a perspective view of an infant's feeding spoon or similar article showing my new design.

FIGURE 2 is a side elevational view.

FIGURE 3 is a top plan view.

FIGURE 4 is a bottom plan view.

FIGURE 5 is a front end elevational view.

FIGURE 6 is a rear end elevational view.

I claim:

The ornamental design for an infant's feeding spoon or similar article, substantially as shown.
